UNITED STATES PATENT OFFICE.

EDWIN G. VAN ZANDT, OF ST. LOUIS, MISSOURI, ASSIGNOR TO VAN ZANDT GAS APPLIANCE COMPANY, OF ST. LOUIS, MISSOURI, A CORPORATION OF MISSOURI.

GAS-BURNER.

1,045,473.

Specification of Letters Patent.

Patented Nov. 26, 1912.

Application filed December 14, 1909, Serial No. 533,053. Renewed July 18, 1912. Serial No. 710,284.

To all whom it may concern:

Be it known that I, EDWIN G. VAN ZANDT, a citizen of the United States, and a resident of the city of St. Louis and State of Missouri, have invented certain new and useful Improvements in Gas-Burners, of which the following is a specification.

This invention relates to gas-burners, and more particularly to those of the Bunsen type, and has for its object to produce a burner which will bring about as complete a combustion of gas as possible in that gas and air-mixture is ignited while passing out of the burner in a finely divided state.

15 In the accompanying drawing, Figure 1 is a front view of an embodiment of my invention. Fig. 2 is a central vertical sectional view of the same, and Fig. 3 is a fragmental sectional view of a detail.

20 Similar reference characters indicate corresponding parts throughout the several views.

Referring to the drawing, the pipe 5 is connected with a suitable supply of gas and 25 with a mixer, whereby the gas is intimately mixed with the proper supply of air.

The burner itself consists of two parts or members, a lower member 6 and an upper member 9. The lower member is of flaring 30 shape and has a flanged rim 7 at its lower part adapted to surround the pipe 5, and a flanged rim 8 at its upper part adapted to surround the other member 9 of the burner. The member 6 fits snugly around the member 9 and is so tightly clamped thereon by reason of the expansion to which the flange 7 is put, that no air may pass between the members. The upper member 9 consists of a top-plate 10 and a plurality of ribs 12 35 separated from each other by annular openings 11 of a definite width and distance apart, while struts 13 bind the top-plate and the separate ribs 12 together. The member 9 is preferably made of cast material and in 40 the form of a cup having inner vertical ribs, which casting is then subjected to a peripheral cutting so as to provide the casting with a plurality of slots or openings corresponding to the openings 11, the remaining material of the wall of the cup forming the ribs 12 and the vertical ribs forming the struts 13.

In the embodiment shown in Figs. 1 and 2 the ribs 12 as also the plate 10, are provided with inclined surfaces 15 which serve

to form outwardly-flaring or V-shaped openings and bring about thereby a spreading of the gas during its ignition. These outwardly flaring openings may also be arranged as to terminate in parallel channels 60 as shown in Fig. 3. The member 6 is preferably made of pressed steel and its upper flange 8 surrounds the lowest rib of the member 9. The member 9 is of larger diameter than the pipe 5, and the member 6 65 is provided with an upwardly-inclined surface, so that the gas when passing out of the upper end of the pipe 5 spreads when entering the member 9, and the member 9 thus acts as a reservoir or gas-container prior to 70 the ignition of the gas. The gas is then caused to pass out of the openings 11 and is thus subjected to a division, or spreading partly on account of the outwardly-flaring shape of the openings 11 and at the exterior 75 of which shell the spread portions of gas are ignited. By thus dividing up the stream of gas into separate smaller streams, the ignited portions thereof are capable of being acted upon to a considerable degree by the 80 oxygen of the air, and thereby a very good combustion of the gas is secured. The struts 13, which, in the embodiment shown in the drawing, are six in number, also serve to bring about a spreading of the gas, so that 85 there are really six circumferentially-arranged flames for every rim, and in the embodiment shown in the drawing there would be four times six, that is, twenty-four separate flames. By collecting the gases in the 90 member 9 prior to their ignition, the same are necessarily heated to some extent by reason of the heating of the member 9. The member 9 has nothing whatever in the interior thereof, so that there is nothing in any 95 manner obstructing the radially equal flow of gas from the interior of the member 9 to the exterior thereof; in other words, the flame is of the same intensity at all the exterior parts of the member 9.

100 My invention therefore consists of an improved burner having an inverted cup-shaped member provided with a plurality of outwardly-flaring contiguously placed annular openings, and further in providing the 105 interior of the openings with inner parallel channels, and in arranging the openings so as to be V-shaped, and further in the gas burner comprising a cup-shaped member and a flaring lower member secured at its upper 110

part to the lower part of said cup-shaped member, and lastly, in providing such a burner with vertical ribs integral with the annular ribs.

5 I have shown several embodiments of my invention, but I do not wish to limit myself to the same, since changes may be made therein without departing from the spirit of my invention.

10 I claim as new:

1. In a gas-burner, an inverted cup shaped member provided with a plurality of horizontally disposed outwardly flaring contiguously placed annular openings.

15 2. A gas-burner comprising an inverted cup-shaped member provided with a plurality of horizontally disposed outwardly-flaring annular openings contiguously placed, and a flaring lower member secured at its 20 wider part to the lower part of said cup-shaped member.

25 3. A gas-burner comprising an inlet-pipe, a one-piece inverted cup-shaped member having vertical ribs on the inner face of the walls of said member, said walls being pro-

vided with a plurality of horizontally disposed outwardly-flaring openings, whereby outwardly-tapering annular ribs are formed integral with said vertical ribs, and an upwardly and outwardly flaring lower member provided with upper and lower annular flanges shrunk upon said cup-shaped member and said pipe respectively. 30

4. In a gas-burner, an inverted cup-shaped member provided with a plurality of V-shaped contiguously placed annular openings. 35

5. In a gas-burner, an inverted cup-shaped member provided with a plurality of outwardly-flaring contiguously placed annular 40 openings, the interior of said openings terminating in parallel channels.

In testimony, that I claim the foregoing as my invention, I have signed my name in presence of two subscribing witnesses.

EDWIN G. VAN ZANDT.
